UNITED STATES PATENT OFFICE.

KARL E. DUNBAR, OF PITTSBURGH, PENNSYLVANIA.

TWO-CYCLE ENGINE.

1,123,861.

Specification of Letters Patent. Patented Jan. 5, 1915.

Application filed January 27, 1912. Serial No. 673,929.

To all whom it may concern:

Be it known that I, KARL E. DUNBAR, a citizen of the United States, residing at No. 6732 Frankstown avenue, in the city of Pittsburgh, in the county of Allegheny and State of Pennsylvania, have invented a new and useful Improvement in Two-Cycle Engines, set forth in the annexed specification.

The object and nature of my said invention is the furnishing and providing of a simple economic and practicable two-cycle engine or motor, that will create or generate power or force by means of the compression and explosion of ordinary operating gases, liquids or explosives, by the compression and explosion of any or all of the said gases, vapors or explosives, in the same power unit, in a more practical, simple, advantageous and economic manner, than by crank case or any other manner of compression now known or used for such purposes.

Figure 1 of the drawing shows a vertical sectional view of the construction of an engine or motor using my invention, at the end of the explosion or power stroke. Fig. 2 of my said drawing shows a side view of the piston together with the gas conveyer attached. Fig. 3 of said drawing shows a plan view of the piston looking up or toward the piston head. Fig. 4 is a cross-sectional view on the line 4—4, Fig. 1. Fig. 5 of my said drawing shows a vertical sectional view of the construction of an engine or motor using my invention, at the end of the upward or backward stroke of the piston. Fig. 6 is a partial cross sectional view of the cylinder showing the top of the gas conveyer closed. Figs. 7 and 8 are detail views of the same. Fig. 9 shows a modification eliminating the traveling gas conveyer.

My invention comprises a motor or engine with cylinders of three different diameters, as shown in Figs. 1, 4 and 5. Beginning at the top of the vertical sectional view in Fig. 1, with the small cylinder "E" named the power or explosion chamber, the next or largest cylinder "V" which forms the outer boundary of the compression chamber, designated by the letter "B" shown in Fig. 5; and ending with the cylinder of the second diameter marked "T" in Figs. 1 and 5. The cylinder "T" is cast or made separate from the cylinders "E" and "V" in order to admit the piston "H—K—I." The cylinder "V" is cast or made with the flange "X." The cylinder "T" has the flange "U" and these two flanges "X" and "U" are bolted or fastened together in a suitable manner, thus connecting the three cylinders as shown in Figs. 1 and 5. Or these cylinders may be fastened together in another manner, instead of the large cylinder "V" and second cylinder "T" being bolted together as shown at the flanges "U" and "X," the flange "X" may be made on the bottom of the explosion cylinder "E," and the flange "U" on the top edge of the cylinder "V," just simply a different place to fasten the machine together, or the cylinders may all be cast or made separately and fastened together in a suitable manner. The purposes of each cylinder may be explained in the same order as above: first, the top or small cylinder "E," Figs. 1 and 5, is the chamber into which the compressed gases or vapors are admitted and exploded to create or generate the power or force which drives the engine or motor; the second or largest cylinder "V," Figs. 1 and 5 forms the outer boundary of the chamber where the gases or vapors are drawn in and primarily compressed; the third, or cylinder "T," Figs. 1 and 5, which is second in diameter is used to keep the expanding rings "R" in the compression sleeve "I" from springing out of place, and is the cylinder in which the compression sleeve "I" operates and prevents the compressed gases or vapors from escaping in that direction. There is also a piston composed of three sections, the diameters of which correspond with the diameters of the three cylinders before mentioned, in which each one of these sections of the piston must respectively fit and operate. These sections may be made or cast all in one piece or made or cast separately and fastened together in a suitable manner. Commencing with the smallest section of the piston, called the piston head, "H," Figs. 1, 2, 3 and 5, which works in the power or explosion chamber "E;" next in order is the largest section "K," Figs. 1, 2, 3, and 5, which I have named the compression ring, this compression ring "K" works in the largest cylinder "V," Figs. 1 and 5. The third section "I" which I call the compression sleeve, is second in diameter and fits into and works in the cylinder "T," Figs. 1 and 5.

The compression chamber, lettered "B" in Fig. 5, is a circular or ring-like chamber formed by the cylinder "V," the compression ring "K," the compression sleeve "I" 5 and the flange "U."

The compression sleeve "I" is used to form the inner wall of the compression chamber "B," Fig. 5, and thus prevent the escape of compressed gases or vapors in that direction, 10 also to overcome loss of suction while the vaporized gases or liquids are being drawn or sucked into the compression chamber "B" through the port "A," by the compression ring "K" receding and acting as a pump 15 when the piston ascends or makes the backward stroke. When the piston "H-K-I" ascends or recedes, as a unit as it must do, being cast or made in one piece, or fastened together in a suitable manner, a suction is 20 created in the compression chamber "B"; this chamber "B" constantly increasing in volume as the compression ring "K" recedes or ascends in the compression cylinder "V," until the end of the backward or upward 25 stroke is completed (Fig. 5); by the suction thereby formed the vaporized or aerated liquids are sucked in from the carburetor, if one is used, or from whatever other means is used, past a suitable valve or cut off "AA" 30 through the port "A" (Fig. 5); this valve or cut off "AA" being open while a proper charge of the vaporized or aerated liquid is being drawn or sucked into the compression chamber "B," and closed while the compression 35 is being made, and until the compression chamber "B" is ready to draw in the next charge of the gas or liquid. This valve "AA" may be located at the port "A" or at any proper distance from the port "A." 40 The valve or cut off may be of any suitable design.

When the compression ring "K" has reached the end of the upward or backward stroke it begins to descend or go forward, and 45 an explosion of the compressed gases or vapors from the preceding charge occurs in the power or explosion chamber "E" above described, and the compression ring "K" is thus forced downward or forward on the 50 power stroke thereby primarily compressing the charge previously drawn into the compression chamber "B;" as the compression ring "K" descends the compression chamber "B" becomes smaller thereby compressing 55 the gases or vapors into a smaller space and forcing the said gases or vapors through the opening or hole "C" (Figs. 1 and 3) into the tube "G," which tube "G" (Figs. 1, 2, 3 and 5) is securely attached or fastened 60 to the compression ring "K" in a suitable substantial and durable manner, and thus works in the same direction and at the same rate of speed as the compression ring "K."

As the tube "G" which I have named the 65 gas conveyer and shall call it such here-

after, descends or moves forward in the tubular chamber "Z" (Fig. 1) the compressed gases or vapors are forced out of the compression chamber "B" through the opening "C" into the gas conveyer "G" and 70 the tubular chamber "Z;" when the compression ring "K" has nearly reached the end of the downward or power stroke, the gas conveyer "G" being attached to the compression ring "K," will be drawn down the 75 same distance and begin to uncover the port "D" in the explosion chamber "E," and when the power stroke is completed, the top of the gas conveyer "G" will be on a level with or opposite to the bottom or lower side 80 of port "D" (Fig. 1), thus uncovering the port "D" completely, allowing the compressed gases or vapors to escape freely into the power or explosion chamber "E" (Fig. 1). At the same time the exhaust 85 port "F" is opened or uncovered by the piston head "H" allowing the burnt or exploded gases to escape (Fig. 1). As the piston head "H" ascends or makes the backward stroke, the gases or vapors that have 90 entered the power or explosion chamber "E" through the port "D" are again compressed by the receding action of the piston head "H" for the next explosion in the power 95 chamber "E" (Fig. 5); the port "D" is then 95 covered or closed by the gas conveyer "G" rising or going backward in the tubular chamber "Z," reaching the top, or near the top, of the chamber "Z" (Fig. 5) when the explosion occurs in the power chamber "E," 100 thus closing or covering the port "D" completely and preventing any loss of power or danger of the exploding gases or vapors from entering the compression chamber "B," through the gas conveyer "G." Attention 105 is also called to the fact that the exhaust port "F" is closed at this time by the piston head "H" (Fig. 5).

The sleeve "Q" containing the diagonal slots and bars at the port "D" (Figs. 1 and 4) is for the purpose of keeping the expanding rings "R" on the gas conveyer "G" from coming out in the port "D" which surrounds the gas conveyer "G." (This however may also be accomplished by casting 110 these diagonal bars in port "D.") The idea and purpose remains the same regardless of the manner in which these slots and bars are made to occur around the port "D." The port "D" surrounds the gas conveyer "G" in the manner shown in Figs. 1, 4 and 5 so that when the explosion takes place in the power or explosion chamber "E" the pressure that backs into the port "D" will 115 be equal all around the gas conveyer "G" and thus prevent unequal wearing. Having this port "D" formed or made in the manner shown in Figs. 1 and 4 also allows freer admission of the gases or vapors into the explosion chamber "E" when the gas 120 125 130

conveyer "G" has uncovered the port "D" (Fig. 1).

The strainer "L" (Fig. 1) may be used or left out altogether, or a strainer of another design may be used. The strainer "L" is tubular in form and perforated, having 5 gauze wire screen fastened in its base or lower extremity so that the screen may be taken out and cleaned. The strainer "L" has a flange at its upper or backward 10 extremity which is broad enough to be caught and held in place by the cap "M." The strainer "L" should be long enough to extend down into the hollow gas conveyer "G" 15 when the power stroke is complete, so as to prevent the strainer from working out of place (Fig. 1).

The cap "M" shown in Figs. 1 and 5 closes the top of the tubular chamber "Z" 20 and prevents the escape of the gases or vapors in that direction: it also holds the sleeve "Q" and the strainer "L" in place.

Wherever the letter "R" appears in the Figs. 1, 2 and 5 it indicates expanding rings, 25 and as these rings are all of similar construction, and used for the same purpose, that is, to prevent the escape of gases, it was not considered necessary to use a different letter or set of letters to indicate each ring.

Letter "S" shown in Figs. 1 and 5 indicates grooves cut in the base of the compression sleeve "I" for the purpose of carrying 30 some of the splashed oil into the cylinder "T" in order to lubricate these parts.

Letter "J" shown in Figs. 1, 2 and 5 indicates ports or openings cut through the base of the piston head "H" above the compression ring "K" for the purpose of preventing compression above the compression 35 ring "K" by allowing the air to work in and out of the chamber formed above the compression ring "K" (Fig. 1). The openings "J" will also admit some of the splashed oil into the said chamber and help 40 to lubricate in this manner. Compression may also be prevented in the chamber above the compression ring "K" in another manner, by leaving an opening in a suitable part 45 of the top of the cylinder "V," this however I consider an inferior method as it allows 50 dust and dirt to be drawn into the cylinder from the outside and does not allow of any chance for lubrication from the splashed oil.

The letter "P" shown on the top of the 55 cap "M" Figs. 1 and 5 indicates the location of a relief, or safety cock or valve.

The letters "PP" shows the location of a combination spark plug, relief or safety cock or valve and priming cup. (Figs. 1 and 5.) 60 The spark plug may however be placed in this location, and a relief or safety cock or valve and priming cup, at any other suitable point at or near the top of the explosion chamber "E," or the spark plug may be 65 placed at any other suitable point.

Letter "N" in Figs. 1, 2, 3, and 5 is the piston pin which fastens the connecting rod "O" (Figs. 1, 2, 3 and 5) to the piston head "H."

The letter "W" indicates the water jacket 70 (Figs. 1, 4, and 5).

The gas conveyer "G" may be designed in another manner, as follows, the top "CT" may be closed as shown in Fig. 6 and a port or opening cut in the side so that when this 75 opening OG descends far enough in the tubular chamber "Z" to become opposite the port "D" in the explosion chamber, the gases or vapors that would then be compressed in the gas conveyer "G" would be 80 allowed to pass through the opening or port OG at the side and near the top of the gas conveyer "G" which port is covered with perforated material L', and through the port "D" into the explosion chamber "E." 85 If this method is used vents or openings VT would have to be left in the top of the tubular chamber "Z" to prevent air compression here, as the closed top gas conveyer "G" works up and down and would also be supplied with a safety valve OL to provide an exhaust in case the gas should explode before reaching the cylinder or expansion chamber. This design is mentioned in order 90 to cover my invention more completely. The 95 openings HH in the top of the compression chamber are to allow the compression ring to be raised without any compression at its upper end.

All castings, forgings and parts mentioned and described in these specifications, 100 are to be made proportional to attain the ends desired.

I am aware that there are motors that use crank case compression directly, but these 105 differ widely from my invention in the manner of confining the gases or vapors while they are being primarily compressed, also in conveying the said gases or vapors into the power or explosion chamber. There 110 is also a motor that uses a compression chamber, but it is vastly different from my invention, in its action, construction, manner of confining the compressing gases or vapors, and system of delivering these 115 gases or vapors into the power or explosion chamber. This motor differs from mine by making the primary compression on the upward or backward stroke of the piston, and forcing the said gases or vapors through a 120 tube or cylinder into the explosion or power chamber of a separate and distinct unit. My invention makes the primary compression on the downward or power stroke of the piston, and by my system the gases or vapors are conveyed or forced into the explosion or power chamber of the same unit, where a further compression takes place on the backward or receding stroke of the piston head, thereby making it possible to have 125 130

a perfect, practicable, and simple, single unit motor, complete in itself.

By direct double compression I mean that with my invention the gases or vapors are primarily compressed by the explosion or power stroke of the piston, by the compression ring in the compression chamber, before described, and that the said compressed gases or vapors, after being thus compressed, are forced or conveyed into the explosion or power chamber through a port or opening in the side of said chamber at or near its upper extremity, where the gases or vapors are again compressed by the receding action of the piston, before explosion. The compressed gases or vapors, however may be admitted into the explosion chamber through a port or opening in the side of said chamber at or near the bottom of said chamber and still use my system of compressing and conveying the gases or vapors. If this system is used it will be necessary to have a small deflector DF on the top or end of the piston head, to prevent the fresh charge from the passageway GG from blowing straight through and out of the exhaust. The compressed gases or vapors however may also be conveyed and admitted into the explosion or power chamber through a port or opening AG in the side of said chamber at or near the bottom of said chamber, after the gases or vapors are drawn in and compressed by my design of compression chamber, and without using my system of conveying, but by using the tube or gas passageway in Fig. 10 connected from the port or opening CS in the lower part of the compression chamber V to the port or opening AG in the side of the explosion chamber E at or near the bottom of said explosion chamber. The explosion chamber E and the cylinder I may also be of the same diameter as shown in Fig. 9. The letters AC in Fig. 9 indicate the strainer to prevent popping back.

What I claim as my invention and desire to secure by Letters Patent is:—

1. An internal combustion engine having an explosion chamber, a piston within the same, a crank case and compression chamber below said explosion chamber and of greater diameter than the same, a compression ring connected to said piston for compressing explosive mixture in the said compression chamber, means connected to said compression ring for preventing the escape of the compressed gas into the crank case, and means connected with said compression ring for conveying said compressed gas to said explosion chamber.

2. An internal combustion engine having an explosion chamber, a piston within the same, a compression chamber below said explosion chamber, means connected to said piston for compressing explosive mixtures

in said compression chamber, a passageway communicating with said explosion chamber and said compression chamber, a traveling conveyer attached to said means for regulating the admission of explosive mixture from said passageway to said explosion chamber.

3. An internal combustion engine having an explosion chamber, a piston within the same, a compression chamber below said explosion chamber, compressing means connected to said piston for compressing explosive mixtures in said compression chamber, a passageway communicating with said explosion chamber and said compression chamber, and a tube connected to said compressing means operating in said passageway for regulating the admission of explosive mixture to said explosion chamber.

4. An internal combustion engine having an explosion chamber, a piston within the same, a compression chamber below said explosion chamber and of greater diameter than the same, compressing means connected to said piston for compressing explosive mixtures in said compression chamber, means connected to said compression means for preventing the escape of the compressed gas into the crank case, a passageway communicating with said explosion chamber and said compression chamber, means connected to said compressing means operating in said passageway for regulating the admission of explosive mixture to said explosion chamber, and means for preventing the popping back of the flame from said explosion chamber.

5. An internal combustion engine having an explosion chamber, a piston within the same, a compression chamber below said explosion chamber, compressing means connected to said piston for compressing explosive mixtures in said compression chamber, a passageway communicating with said explosion chamber and said compression chamber, a tube connected to said compression means operating in said passageway for regulating the admission of explosive mixture to said explosion chamber, and means for preventing the popping back of flame from said explosion chamber.

6. An internal combustion engine having an explosion chamber, a piston within the same, a compression chamber below the said explosion chamber and of greater diameter than the same, compressing means connected to said piston for compressing explosive mixtures in said compression chamber, means connected to said compressing means for preventing the escape of the compressed gas into the crank case, a passageway communicating with said explosion chamber and said compression chamber, means connected to said compression means operating in said passageway for regulating the admission of explosive mixture to said explosion chamber.

explosive mixtures to said explosion chamber, and screen means for preventing the popping back of flame from said explosion chamber.

- 5 7. An internal combustion engine having an explosion chamber, a piston within the same, a compression chamber below said explosion chamber, compressing means connected to said piston for compressing explosive mixtures in said compression chamber, a passageway communicating with said explosion chamber and said compression chamber, a tube connected to said compression means and operating in said passageway for regulating the admission of explosive mixture to said explosion chamber, and screen means for preventing the popping back of flame from said explosion chamber.
- 10 8. An internal combustion engine having an explosion chamber, a piston within the same, a crank case, a compression chamber below said explosion chamber and of greater diameter than the same, a compression ring connected to said piston for compressing ex-
